UNITED STATES PATENT OFFICE.

GEORGE H. ULLMAN, OF NEW YORK, N. Y., ASSIGNOR TO L. PLAUT & CO., OF NEW YORK, N. Y., A COPARTNERSHIP.

DESIGN FOR A PLAQUE FOR LIGHTING-FIXTURES.

No. 40,165.

Specification for Design.

Patented July 20, 1909.

Application filed March 30, 1909. Serial No. 486,832. Term of patent 7 years.

To all whom it may concern:

Be it known that I, GEORGE H. ULLMAN, a citizen of the United States, and a resident of the borough of Manhattan, city, county, and State of New York, have invented a new, original, and ornamental Design for a Plaque for Lighting-Fixtures, of which the following is a specification, reference being had to the accompanying drawing, forming a part hereof, which shows a plan view of the design.

The design comprises a plaque of substantially circular shape with a wavy border.

In the center of the plaque is a representation of leaves and fruit with branches inclosing such arrangement, the whole being substantially circular. The branches radiate toward the periphery of the figure and carry representations of leaves and fruit.

I claim:

The ornamental design for plaque for lighting fixture, as shown and described.

GEORGE H. ULLMAN.
